UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed October 31, 1927. Serial No. 230,034.

This invention relates to mining machines and more particularly, but not exclusively, to coal mining machines of the wheel mounted "universal" type adapted to operate from the mine trackway.

An object of this invention is to provide an improved coal mining machine of the wheel mounted type. Another object of this invention is to provide an improved coal mining machine of the wheel mounted "universal" type adapted to operate either as a horizontal cutter or a shear cutter. A further object of this invention is to provide an improved coal mining machine of the combined horizontal and shear cutter type wherein the cutter bar may be expeditiously adjusted into a plurality of operative positions. Yet another object of this invention is to provide improved controlling means for the various clutches controlling the cutter head rotating mechanism, the truck driving mechanism, and the plural speed transmission mechanism whereby the same may be conveniently and expeditiously controlled. These and other objects and advantages of this invention will, however, subsequently more fully appear as the description proceeds.

In the accompanying drawings there is shown for purposes of illustration one form which the invention may assume in practice.

In these drawings,—

Fig. 1 is a plan view of a coal mining machine with which one illustrative embodiment of the invention is incorporated.

Fig. 2 is a side elevational view of the machine shown in Fig. 1, the machine being shown in its lowered position.

Fig. 3 is a horizontal longitudinally extending sectional view taken on line 3—3 of Fig. 2, parts being shown in plan.

Fig. 4 is a horizontal longitudinally extending sectional view taken on line 4—4 of Fig. 2, the view being shown partially in plan.

Figs. 5 and 5a are detail sectional views taken on lines 5—5 and 5a—5a respectively of Fig. 4.

Fig. 6 is a detail view illustrating the control handle for the reverse controlling fric-

tions of the elevating and tilting mechanism for the machine body.

Fig. 7 is a transverse vertical sectional view taken on line 7—7 of Fig. 3.

Fig. 8 is a transverse vertical sectional view taken on line 8—8 of Fig. 3.

Fig. 9 is a transverse sectional view taken on line 9—9 of Fig. 4.

Fig. 10 is a somewhat diagrammatic view illustrating the elevating and tilting means for the machine body, different positions thereof being illustrated by dotted lines.

Fig. 11 is an enlarged fragmentary plan view with parts shown in sections illustrating the improved controlling arrangement for the controlling clutches of the various devices.

Fig. 12 is an enlarged detail sectional view illustrating a portion of the improved controlling means taken on line 12—12 of Fig. 11.

Fig. 13 is a transverse sectional view taken on line 13—13 of Fig. 12.

Fig. 14 is a detail sectional view taken on line 14—14 of Fig. 11.

Fig. 15 is a detail sectional view taken on line 15—15 of Fig. 11.

Fig. 16 is a detail sectional view taken on line 16—16 of Fig. 11.

Fig. 17 is a detail view illustrating the improved truck wheel braking means.

In this illustrative embodiment of the invention there is shown a mining machine of the same general type as that described in my copending application Ser. No. 137,600, filed September 24, 1926, now matured in Patent No. 1,785,961, patented December 23, 1930. As shown, the improved mining machine is designated as an entirety by the reference character 1, the machine being of the so-called "universal" type mounted on wheels and operating from the mine trackway. The mining machine 1 generally comprises a machine body 2 rotatably mounted about its longitudinal axis on the truck frame and composed of a section 3, herein the cutter carrying head, housing the driving connections for the cutting mechanism and a motor section 4, these sections 3 and 4 being rigidly united and suitably mounted on a wheel 100.

mounted frame generally designated 5. Also mounted on the truck frame 5 is a frame section 6 housing the plural speed transmission means for the truck drive, for rotating the machine body, and for elevating and tilting the machine body. The head 3 has pivotally mounted thereon a usual elongated plane cutter bar 7 having an endless cutter bit carrying cutter chain 8 mounted on its margin. The swinging mechanism for the cutter bar and the driving connections for the cutter chain are clearly described in my co-pending application mentioned above and further description of the same is herein considered unnecessary. The wheel mounted frame 5 includes longitudinally spaced transverse frames 9 and 10 held in rigid spaced relation by parallel longitudinally extending frames or angle members 11, the latter being rigidly secured to the transverse frame members 9 and 10 as by suitable screws 12. These angle members 11 support various devices of the machine as will later be described. As clearly shown in Figs. 3, 7 and 8 the frame members 9 and 10 are respectively provided with semicircular bores 13 which receive aligned bearing sleeves 14 and 15 in which cylindrical portions 16 formed on frame sections 17 and 18 are respectively rotatably mounted, the frame sections 17 and 18 being connected by bolts 19 respectively to the opposite ends of the motor section 4. It will herein be observed that the frame member 17 is preferably composed of two parts to facilitate manufacture, assembly, and the dismantling of the machine. The frame member 17 is also connected by bolts 20 to the cutter carrying head 3. The transverse frame members 9 and 10 are each horizontally split as at 21 and are provided with detachable cap members 22 and 23 respectively, each held in position by suitable screws 24, these caps retaining the bearing sleeves 14 and 15 in position and permitting removal of the cutter carrying and motor frames from their bearings. As illustrated, the frame section 6 which houses the plural speed transmission mechanism for the truck drive, the machine body elevating and tilting mechanism, and bar rotating mechanism is rigidly secured to the longitudinally extending frame members 11 by screws 25, the cutter carrying frame 3 and the motor frame section 4 constituting the machine body 2 being adapted to rotate relative to the frame section 6 as hereinafter more fully described. As illustrated, suitably connected to the transverse frame members 9 and 10 are pivoted supporting arms 26 and 27 which carry the truck wheels 28, the arms 26 and 27 and the wheels 28 constituting the supporting means for the machine.

In specifically describing the truck wheel propulsion mechanism it will herein be noted that housed within the motor section 4 is a

suitable driving motor herein preferably of the usual reversible electric type having a horizontal armature shaft 29 extending longitudinally of the machine. This shaft is journaled at its rear end in ball bearings 30 suitably carried within the frame section 18 as clearly shown in Fig. 3. The armature shaft 29 has secured thereto as by a key 31 a coupling member 32 which is splined at 33 to a shaft 34 disposed in longitudinal alignment with the armature shaft, the front end of the shaft 34 being supported by the member 32 while the rearward end of this shaft is journaled in a ball bearing 35 suitably carried within the frame section 6 as clearly shown in Figs. 3 and 4. This shaft 34 has fixed thereto at its rear end by a key and screw connection 36 a spur pinion 37 which meshes with a larger spur gear 38 (see also Fig. 9), suitably secured to a shaft 39 suitably journaled within the frame section 6. The shaft 39 is disposed parallel with the shaft 34 and slightly below the latter. The shaft 39 has keyed thereto at 40 a worm 41, herein the fast speed worm, which meshes with a worm gear 42. Also secured to the shaft 39 between the worm 41 and the spur gear 38 is a spur pinion 43 which meshes with a larger spur gear 44 secured to a shaft 45 disposed parallel with the shaft 39 and in the same transverse horizontal plane. The shaft 45 has keyed thereto at 46 a worm 47, herein the slow speed worm, which meshes with a worm gear 48. As shown, the worm gears 42 and 48 are journaled on ball bearings 49 carried by a horizontal shaft 50 disposed transversely of the machine and journaled at its opposite ends in ball bearings 51 suitably carried within the frame section 6, the central portion of the shaft 50 being journaled in ball bearings 52 carried within a retaining member 53 suitably supported within an annular split boss 54 formed within the frame section 6. As the clutch mechanisms for connecting the gears 42 and 48 to the shaft 50 to effect rotation of the latter at a fast or at a slow speed are substantially identical, detail description of one will suffice for both. The gear 42 is made hollow and carries therein a series of clutch plates 55 which are interleaved with a corresponding series of clutch plates 56 carried by a clutch member 57 keyed at 58 (see Fig. 9) to the shaft 50. Encircling the clutch member 57 and axially slidable thereon is a clutch applying member 59. Also encircling each of the clutch members 57 and disposed at opposite ends of the shaft 50 are clutch shipper members 60 and 61, suitable ball thrust bearings 62 being interposed between the members 59 and the members 60 and 61, respectively. As clearly shown in Fig. 9 disposed above the shaft 50 and parallel therewith is a plural part actuating rod 63 slidably mounted in bores 64 formed within the frame section 6. Pivoted connected

adjacent the opposite ends of the rod 63 at 65 are clutch shipper yokes 66 which co-operate respectively with clutch shipper members 60 and 61. These clutch shipper yokes 66 are also pivotally connected as at 67 to link members 68, these link members in turn being pivotally connected at 69 to a portion of the frame section 6. As shown the intermediate portion of the actuating rod 63 10 is transversely slotted at the top and bottom thereof at 70 and the bifurcated end of a pivoted lever 71 cooperates with these slots as clearly shown in Fig. 11. The lever 71 is pivoted at 72 on the machine frame. The 15 improved operating connections for this lever will later be described. From the foregoing it is evident that when the lever 71 is swung about its pivot the actuating rod 63 is slid axially, thereby swinging the shipper yokes 20 66 about their pivots 67 consequently applying the desired friction clutch and connecting either the fast speed or the slow speed worm gear in driving relation with the shaft 50. The shaft 50 is herein rotated in the 25 same direction at either a slow speed or a fast speed. As clearly shown in Figs. 4 and 9 suitably secured to one end of the shaft 50 is a bevel pinion 75 which meshes with bevel gears 76 and 77, these gears 76 and 77 rotating in opposite directions and constituting a reversing mechanism, as hereinafter described, for driving the truck wheels and rotating the cutter carrying head in opposite directions. The gears 76 and 77 are each 30 provided with a hub portion 78 journaled on a bearing sleeve 79 carried by a shaft 80, this shaft being disposed at a right angle to the shaft 50 and extending longitudinally of the machine. As illustrated, the shaft 80 is journaled at its opposite ends in suitable ball 35 bearings 81 suitably carried within the frame section 6. Carried within each of the gears 76, 77 is a series of friction clutch plates 82 which are interleaved with a corresponding series of clutch plates 83 respectively carried 40 by clutch members 84 keyed at 85 adjacent the opposite ends of the shaft 80. Encircling the hubs of the gears 76, 77 are clutch applying members 86 having fingers projecting through apertures formed in their respective gears into engagement with the clutch plates. Disposed intermediate the clutch applying members and encircling the hubs of 45 the bevel gears is a clutch shipper member 87, suitable ball thrust bearings 88 being interposed between the clutch shipper member 87 and each of the clutch applying members 86. Cooperating with the peripheral groove formed on the clutch shipper member 87 is a clutch shipper yoke 89 pivotally connected to a trunnion 90 threadedly connected to an actuating rod 91, the latter being slidably mounted with alined bores 92 formed within 50 the frame section 6. The operating mechanism for the clutch shipper yoke 89 will be 55 subsequently described. It will thus be evident that when the clutch housed in one or the other of the bevel gears 76, 77 is applied, the shaft 80 may be rotated in one direction or the other and also at either a fast or a 60 slow speed under the control of the friction clutches 55, 56 for the worm gears 42, 48. 65

As shown, secured to the forward end of the shaft 80 as by a detachable coupling member 93 and alined therewith is a shaft 94 journaled at its forward end in a ball bearing 95 suitably carried within the transverse frame member 10. The shaft 94 has secured thereto at its forward end a bevel pinion 96 which meshes with a larger bevel gear 97 rotatably mounted on a horizontal shaft 98 disposed parallel to the transverse shaft 50 and at a right angle to the shaft 94 as clearly shown in Fig. 3. The shaft 98 is journaled at its opposite ends in alined ball bearings 99 suitably carried by the transverse frame member 10. Herein, preferably formed integral with the bevel gear 97, are clutch teeth 100, while preferably formed integral with the shaft 98 are clutch teeth 101 and these clutch teeth 100 and 101 are adapted to be connected by means of an axially movable internally toothed clutch member 102, thereby causing the gear 97 and shaft 98 to rotate together. The improved actuating mechanism for 70 the clutch member 102 will be subsequently described. Secured to the outer end of the shaft 98 by a screw and key connection 103 is a chain sprocket 104 and this chain sprocket is connected, as clearly shown in Fig. 8, by an 75 endless chain connection 105 to a chain sprocket 106. The chain sprocket 106 is secured by a key and screw connection 107 to a horizontal shaft 108 extending transversely of the machine. Secured to the end of the 80 shaft 108 opposite from the sprocket 106 as by a key and screw connection 109 is a chain sprocket 110. Connected by a dental clutch 85 111 to the inner end of the chain sprocket 110 is a sleeve member 112, this latter member 90 in turn being clutched at 113 to a chain sprocket 114. This sprocket 114 is connected by an endless chain connection 115 to a 95 sprocket on one end of a horizontal axle 116 disposed below and parallel with the shaft 108 and by which the rear truck wheels 28 are 100 carried. The axle 116 is journaled at its opposite ends in suitable roller bearings 117 carried within the lower end of the supporting arm 27. The shaft 108 is journaled at its 105 opposite ends in roller bearings 118 carried within the opposite sides of the transverse frame member 10. As shown in Fig. 8 the upper end of the supporting arm 27 is pivotally mounted for swinging movement on roller bearings 119 supported by the shaft 108. In 110 accordance with this illustrative embodiment of the invention the chain sprocket 110 is connected as by an endless chain connection 120 (see Fig. 10) to a chain sprocket 121 secured 115 125 130

by a key and screw connection 122 to a horizontal shaft 123 (see Fig. 7), the latter being journaled at its inner end in a ball bearing 124 while the outer end of this shaft is 5 journaled in roller bearings 125, these bearings being carried by the frame section 9. As clearly shown in Fig. 7 the chain sprocket 121 is connected by a dental clutch 126 to a sleeve member 127 supported on the shaft 123 and 10 this member 127 is in turn connected by a dental clutch 128 to a chain sprocket 129. The chain sprocket 129 is connected by an endless chain connection 130, similar to the chain connection 115, to a chain sprocket 131 15 keyed at 132 to the front truck axle 133, the latter being disposed parallel with the axle 116 heretofore described. The axle 133 carries the truck wheels 28 and is journaled at its opposite ends in roller bearings 134 carried within the lower end of the supporting arm 26. The upper end of the arm 26 is pivotally mounted for swinging movement on a roller bearing 135 supported at the side thereof adjacent the sprocket 129 on the shaft 123 20 while the other side is supported on a roller bearing 136 supported by a shaft 137 to be later described.

In specifically describing the improved mechanism for bodily rotating the motor casing and cutter carrying head to vary the plane of the cut it will be noted that meshing with the bevel gear 97 (see Fig. 3) is a bevel pinion 138 suitably fixed to the rear end of a shaft 139 alined with the shaft 94 and 30 journaled at its rear end in a ball bearing 140 suitably supported within the frame member 10. The forward end of the shaft 139 is connected by a detachable coupling 141 to the rear end of a shaft 142, the latter being journaled at its forward end in a ball bearing 143 suitably supported by the transverse frame member 9. As shown, the shaft 142 has secured thereto at its forward end a bevel pinion 144 which meshes with a bevel gear 145 35 rotatably mounted on a horizontal shaft 146 disposed parallel with the shaft 98 heretofore described. The shaft 146 is journaled at its opposite ends in alined ball bearings 147 carried by the transverse frame member 9. 40 Herein preferably formed integral with the bevel gear 145 are clutch teeth 148, while preferably formed integral with the shaft 146 are clutch teeth 149 and these clutch teeth are adapted to be connected by means of an 45 axially movable internally toothed clutch member 150, thereby causing the bevel gear 145 and the shaft 146 to rotate together. It will further be noted that secured to the outer end of the shaft 146 by a key and screw connection 151 is a chain sprocket 152 and this sprocket is connected by means of an endless chain connection 153 (see Fig. 7) with a chain sprocket 154 secured by a key and screw connection 155 to the outer end of the shaft 60 137. The shaft 137 is journaled in ball

bearings 156 and roller bearings 157 carried by the transverse frame member 9. The shaft 137 carries adjacent its inner end a worm 158 which meshes with a worm gear 159 (see also Fig. 3) secured by bolts 160 to the frame member 16 and disposed coaxially with the motor axis. The improved actuating means for the clutch member 150 will hereinafter be described. From the foregoing description it will be evident that when the gear and clutch teeth 148, 149 are connected by the clutch member 150, it being understood that the shaft 142 is rotating, the worm gear 159 is consequently rotated and the cutting mechanism may thus be moved to operate in different planes, i. e. a horizontal plane or a vertical plane. 75

In specifically describing the mechanism for elevating and tilting the machine body, it will herein be noted that secured by a key 80 at 161 (see Fig. 4) to the end of the shaft 50 opposite from the bevel gear 75 is a bevel pinion 162 which meshes with bevel gears 163 and 164. The bevel gears 163, 164 are similar to the bevel gears 76 and 77 and likewise 85 rotate in opposite directions and constitute a reversing mechanism. These gears also house friction clutches 165, 166 similar to the clutches within the gears 76, 77 and having a similar central clutch applying member 167. As the specific construction of the clutches 165, 166 and the actuating means therefor has been clearly described in connection with the clutches 82, 83 within the bevel gears 76 and 77, further description 90 thereof is herein considered unnecessary. Cooperating with the peripheral groove formed on the clutch shipper member 167 is a clutch shipper yoke 168 pivotally connected to a trunnion 169 adjustably mounted on a rod 170, the latter being slidably mounted within alined bores 171 formed within the frame section 6. Pivoted on the machine frame at 172 (see also Fig. 6) is an operating handle 173 in the form of a bell crank and having one of its arms 174 projecting within an aperture 175 formed within the rod 170. It will thus be evident that when the operator suitably manipulates the handle 173 the rod 170 is moved axially in the desired direction, thereby effecting application of the desired friction clutch. As shown in Fig. 4 arranged coaxially with the bevel gears 163, 164 is a shaft 176 similar to the shaft 80 and likewise is 100 adapted to be driven in opposite directions through the bevel gearing. The forward end of the shaft 176 is connected by a detachable coupling 177 (see Fig. 3) to the rear end of a screw threaded shaft 178, this shaft 178 being journaled at its forward end in a bearing sleeve 179 suitably supported within a clutch housing 180. The housing 180 is rigidly secured to one of the angle members 11. As illustrated, secured to the forward end 105 of the shaft 178 by a key and lock nut con-

nection 181 is a toothed clutch member 182 which is adapted to be connected by means of an axially movable internally toothed clutch member 183 to a toothed clutch member 184 secured by a key and lock nut connection 185 to the rear end of a similar screw threaded shaft 186 arranged in axial alinement with the shaft 178. This shaft 186 is journaled at its rear end in a bearing sleeve 187 suitably supported within the clutch housing 180. Interposed between a flange 188 formed on each of the shafts 178 and 186 and the hubs of each of the clutch members 182, 184 is a ball thrust bearing 189 and these bearings absorb the axial thrust of the shafts in either direction. These screw threaded shafts are respectively threadedly connected at 190 to non-rotatable nut members 191, 192 of rectangular cross section slidably mounted in suitable guideways 193, these nut members each having formed thereon at the bottom thereof teeth 194 which cooperate with teeth 195 formed on arcuate members 196, 197 secured as by screws 198 to the machine supporting arms 27 and 26, respectively. As shown in Fig. 3 the internal clutch member 183 is adapted to be shifted axially by means of a shipper yoke 199 having an elongated guide portion 200 slidably mounted in a slot 201 or guideway 201 formed within the clutch housing 180. A screw 202 is threadedly connected to the shipper yoke 199 and projects laterally therefrom through an elongated slot 203 formed in the gear housing 180 and this screw carries a resiliently positioned operating member 204, a spring 205 being provided for yieldably maintaining the operating member 204 in engagement with locking apertures in the gear housing. From the foregoing description it will thus be evident that when the clutch members 182, 184 are connected by the clutch member 183, it being understood that the shaft 176 is rotating, the screw threaded shafts 178, 186 are also rotated and consequently the nut members 191 and 192 are moved axially in their guides thereby swinging the machine supporting arms 26 and 27, respectively about their pivots and the machine body is consequently elevated or lowered as desired. Furthermore, it will be noted that if the clutch members 182, 184 are disconnected the shaft 186 remains stationary while the shaft 178 continues to rotate and consequently effecting swinging movement of only the rear supporting arms 27 and as a result tilting the machine body about the front truck axle 133. It is obvious that the arms 26 and 27 may be swung in opposite directions at either a fast or a slow speed.

Now referring to the improved operating mechanism for the friction clutches housed within the fast and slow speed worm gears 42 and 48 it will be noted that the lever 71 shown in Fig. 11 has pivotally connected

thereto a two-part trunnion 207 having housed therein a ball thrust bearing 208 which engages an actuating shaft or rod 209, the latter being horizontally disposed and extending transversely of the machine. The outer end of this rod 209 has keyed thereto at 210 a toothed clutch member 211, the teeth of which are adapted to cooperate with internal clutch teeth 212 formed within a hand wheel 213 encircling the clutch member 211 and slidably axially relative thereto. As illustrated in Fig. 12 the teeth 212 are adapted to cooperate with clutch teeth 214 formed on a pressure screw 215 threadedly connected at 216 to a nut 217, herein preferably formed integral with a bracket 218 rigidly connected by screws 219 to one of the angle members 11 of the truck frame. Interposed between the hub of the clutch member 211 and the pressure screw 215 is a ball thrust bearing 220 while a similar ball thrust bearing 221 is interposed between the pressure screw 215 and a shoulder on the rod 209. It will thus be evident that when the clutch teeth 212 and 214 are connected and upon rotation of the hand wheel 213, the pressure screw 215 is moved axially relative to the stationary nut 217 and as a result the rod 209 is shifted axially, thereby effecting swinging movement of the lever 71. This swinging movement of the lever 71 effects sliding movement of the actuating rod 63, thereby swinging the shipper yokes 66 about their pivots. As a result one or the other of the clutches housed within the fast and slow speed worm gears 42 and 48 is applied while the other clutch is released. Herein preferably formed integral with the rod 209 is a crank or arm 222 pivotally and slidably connected at 223 (see also Fig. 13) to a toggle arm or link 224, the latter in turn being pivotally connected at 225 to a rocker arm 226 keyed at 227 to a horizontal actuating shaft 228 arranged parallel with the shaft 209. The shaft 228 is rotatably mounted within the bracket 218 and a similar bracket carried by the member 11 at the opposite side of the machine. Secured to the opposite end of the shaft 228 (see Figs. 12 and 16) is a bifurcated arm 229 having its projecting ends disposed between spaced collars or abutments 230 secured to the actuating rod 91 for the clutch shipper yoke 89. From the foregoing it is evident that when the hand wheel 213 is shifted outwardly and the clutch teeth 211, 212 connected, and upon rotation of the hand wheel the rod 209 is rotated and this rotative movement is transmitted through the crank 222, toggle link 224, rocker arm 226 to the transverse shaft 228, and as a result the arm 229 is swung laterally, thereby shifting the rod 91 axially and applying one or the other of the clutches 82, 83 within the bevel gears 76 and 77. Consequently one or the other of these bevel gears is connected in driving re-

lation with the shaft 80. Referring more particularly to the improved actuating means for the clutch members 102 and 150 it will be noted that slidably mounted on the rods 209, 228 is a bracket 231 having pivotally connected thereto a shipper handle 232 (see Fig. 11). This bracket 231 is connected by parallel tie rods 233 to a shipper member 234 likewise slidably mounted on the shaft 228. In this instance the shipper member 234 has formed thereon upstanding parallel portions 235 having formed therein oppositely disposed cam slots 236 and 237, respectively, each of these slots having an inclined portion 236^a and a horizontal portion 237^a. Cooperating with the cam slot 236 is a pin 238 carried on the outer end of a lever 239 secured by a set screw 240 to a horizontal actuating shaft or rod 241, the latter being disposed longitudinally of the machine as clearly shown in Fig. 11. This rod 241 is connected by a coupling 242 to a rod or shaft 243 rotatively mounted at its forward end within the transverse frame member 9. This rod 243 has splined thereto at 244 a shipper yoke 245 (see also Fig. 7) which cooperates with the peripheral groove formed on the clutch member 150. Cooperating with the cam slot 237 is a pin 246 (see Fig. 11) carried by the outer end of a lever 247 fixed to a two-part clutch connected sleeve or hollow shaft 248 within which the rod 241 is rotatably mounted, this sleeve being suitably journaled on the transverse frame member 10. As shown, keyed to the forward end of the sleeve 248 at 249 is a shipper yoke 250 (see also Fig. 8) which cooperates with the peripheral groove formed on the clutch member 102. From the foregoing it will be evident that when the operator grasps the handle 232 and slides the shipper member 234 lengthwise of the shaft 228 one of the levers 239, 247 remains stationary, the pin carried thereby entering the horizontal portion 237^a of the cam slot while the other lever is swung downwardly by the cam and as a result one of the clutch members 102, 150 is shifted into operative position while the other clutch member is maintained released. When the shipper member 234 is shifted in the opposite direction the other clutch is connected while the first mentioned clutch is released. It is accordingly evident that the cutter carrying head rotating mechanism and the truck driving mechanism are only alternatively connected in driving relation with the motor.

As illustrated, electric current is adapted to be conducted to the electric driving motor 4 through suitable conductor cables 251, 252 and 253 (see Figs. 1 and 4). The cable 251 passes through a suitable guiding device 253^a and is connected to a suitable cable reel 254 journaled at 255 upon a bracket member 256 rigidly secured to the rear ends of the angle members 11. Suitable slip ring connections,

not shown, are provided between the reel and connector plugs 257, the cables 252, 253 leading respectively from these connector plugs through certain electrical devices to a housing member 258 carried at the top of the transverse frame member 10 (see Figs. 1, 2 and 8). The wires housed within the conductor cable are connected through suitable terminals 259 and wires 260 to resilient contact members 261 suitably secured to the cap member 267 has housed therein a ratchet ably engage slip rings 262 secured for rotation with the casing of the motor. It will thus be evident that the slip rings 262 rotate bodily with the motor casing and current is adapted to be supplied through these slip rings and the contacts to the motor irrespective of the position of the motor frame relative to the truck frame 6. The cable reel 254 is adapted to be rotated by power, and mechanism for accomplishing this is clearly shown in Fig. 4. Secured by a key 265 to the rear end of the shaft 80 is a clutch member 266 which is adapted to be frictionally connected to a clutch member 267 by means of a clutch applying member 268. The member 268 is normally automatically maintained in applied position by means of suitable coiled springs 268^a. The hub of the clutch member 267 has housed therein a ratchet mechanism including a spring pressed pawl 269 adapted to cooperate with a tooth 270 formed on the member 267. The pawl 269 is carried by a shaft 271 connected through a universal joint 272 to a shaft 273. The shaft 273 has fixed thereto at its rear end a bevel pinion 274 which meshes with a bevel gear 275 rigidly fixed to the reel shaft. The pawl 269 carried by the shaft 271 may be manually released from engagement with the tooth 270 on the clutch member 267 by means of a member 276, herein in the form of a hand wheel, rotatably mounted on the shaft 271 (see Fig. 5). This member has formed thereon an arcuate slot or notch 277 in the form of a cam, the curved surface of which is adapted to engage the pawl 269. Upon rotation of the member 276 in either direction the pawl is forced inwardly, thereby releasing the clutch member 267 from the shaft 271 and disconnecting the reel drive. Spring pressed plungers or balls 278 carried by the shaft 271 are adapted to engage suitable apertures 279 formed on the hand wheel to maintain the latter in its different adjusted positions. It is evident that when the pawl 269 engages the tooth 270 the shaft 80 may be rotated in one direction to drive the reel and upon rotation of the shaft 80 in the opposite direction the pawl 269 slips over the tooth 270 thereby disconnecting the reel drive. It is therefore obvious that the cable reel can be driven by power in only one direction.

Improved braking means is also provided

for controlling rotation of the truck wheels and this means comprises rotatable brake drums 280, 281 fixed respectively to the shafts 123 and 108 (see Figs. 7, 8 and 17). 5 Cooperating with these brake drums are brake bands 282 and 283 respectively, and these bands are adapted to be contracted and expanded by means of suitable toggle lever mechanisms 284 and a connecting pull rod 285. A suitable operating lever 286 is provided having ratchet means 287 for holding the same in its different adjusted positions. It is obvious that by a mere pull on the lever 286 the brakes may be simultaneously applied, thereby preventing rotation of the shafts 123, 108 which are connected to the truck wheels.

The general mode of operation of the improved mining machine is as follows: When it is desired to propel the machine along the trackway in the main entry at a fast or transport speed the operator grasps the hand wheel 213 and slides the same inwardly, thereby connecting the clutch teeth 212, 214 and upon rotation of this hand wheel the pressure screw together with the rod 209 are moved inwardly, thereby swinging the lever 71 about its pivot and applying the friction clutch 55, 56 connecting the fast speed worm gear 42 to the shaft 50. The operator then disconnects the clutch teeth 212, 214 and slides the teeth 212 into engagement with the teeth on the clutch member 211 and upon rotation of the hand wheel 213 the rod 209 is rotated and this rotative movement is transmitted through the arm 222, toggle link 224, rocker arm 226 to the rock shaft 228, and as a result the rod 91 is slid axially, thereby applying the clutch 82, 83 connecting the bevel gear 76 to the shaft 80. When the working face of the coal is reached these clutches are then released. It is obvious that upon application of the clutch 82, 83 connecting the bevel gear 76 to the shaft 80 the direction of rotation of the latter is reversed and the machine is propelled rearwardly at a fast speed. If it is desired to make a horizontal cut the swinging mechanism for the cutter bar 7 is suitably connected to the motor 45 and the cutter bar is swung or slued about its pivot at a fast speed to a point adjacent the right hand rib in a manner clearly described in my copending application mentioned above. The driving mechanism for the cutter chain 8 is then connected to the motor and the cutter chain is rapidly circulated about the margin of the cutter bar. The operator then again slides the hand wheel 213 inwardly, connecting the clutch teeth 212, 214 and upon rotation of the hand wheel the rod 209 is moved axially thereby swinging the lever 71 about its pivot, thereby applying the friction clutch 55, 56 for connecting the slow speed worm gear 48 to the shaft 50. 60 The operator then disconnects the teeth 212,

214 and slides the teeth 212 into engagement with the teeth on the clutch members 211 and upon rotation of the hand wheel the rods 209, 228 are rotated, and as a result, the rod 91 is moved axially, applying the clutch 82, 83 connecting the bevel gear 76 to the shaft 80. The operator then grasps the lever 232 and shifts the shipper member 234 inwardly, the cam slot 237 forcing the lever 247 downwardly, thereby connecting the clutch 100, 101, 102 70 and the cutter bar is sumped or fed into the coal at a slow or cutting speed, the machine moving bodily along the trackway. When the sumping cut is completed the operator swings the lever 286, thereby effecting application of the brakes 282, 283 which prevent rotation of the shafts 123, 108 and consequently the truck wheels are held against rotation. The cutter bar is then swung about its pivot to effect the swinging cut at a cutting speed, the slow bar swinging mechanism thereafter being released. The truck wheel brakes are then released and the operator again connects the clutch 100, 101, 102 and the clutch 82, 83 connecting the bevel gear 77 to the shaft 80, reversing the rotation of the shaft and the cutter bar is withdrawn from the coal at a cutting speed. If it is desired to make the shear cut the operator grasps the lever 232 and shifts the shipper member 234 outwardly, thereby 80 swinging the lever 239 downwardly and connecting the clutch 148, 149, 150, thereby causing rotation of the worm 158 and worm gear 159 and the cutter carrying head and motor casing are bodily rotated into a vertical position within the bearings 14 and 15. The worm 158 and worm gear 159 maintain the bar rotating mechanism in its adjusted position at this time, the worm and worm gear being self-locking. The cutter bar is then 90 swung upwardly about its pivot at a fast speed to a point adjacent the mine roof. The cutter bar is thereafter sumped into the coal at a cutting speed, the machine moving bodily along the trackway at that time. The cutter bar is then swung downwardly at a 95 cutting speed to the bottom of the mine and the bar is thereafter withdrawn at a cutting speed from the coal in a manner substantially similar to that heretofore described in regard to the horizontal cut. If it is desired to vary the elevation of the cutter bar of the machine body the clutch 182, 183, 184 is connected. The friction clutch 166 is then applied, connecting the bevel gear 164 to the shaft 176, it being understood that the clutch 55, 56 connecting the slow speed worm gear 48 to the shaft 50 is still applied, and as a result the screw threaded shafts 178, 186 are simultaneously rotated, thereby sliding the nut elements 191, 192 in their guideways and swinging the gear segments 196, 197 and consequently moving the machine body upwardly to the desired elevation. If it is desired to lower the machine the friction clutch 165 100

connecting the bevel gear 163 to the shaft 176 is applied and the gear segments 196, 197 are swung in the opposite direction, consequently lowering the machine body. If it is desired to tilt the cutter bar the clutch 182, 183, 184 is disconnected and upon rotation of the screw threaded shaft 178 the threaded nut 191 is moved in its guideway while the nut member 192 remains stationary, thereby causing only the rear supporting arm 27 to be swung about its pivot, and as a result the machine is swung about the front truck axle, thus varying the angle of the machine body relative to the horizontal and consequently the angle of the cutter bar relative to the mine bottom. It is obvious that by simply rotating the handwheel 276 the cable reel 254 may be connected to the motor to wind in the conductor cable 251. Other operations and advantages of this invention will be clearly apparent to those skilled in this art.

While I have in this application specifically described one form which my invention may assume in practice, it will be understood that this form of the same has been shown for purposes of illustration and that the invention may be modified and embodied in various other forms without departing from its spirit or the scope of the appended claims.

What I claim as new and desire to secure by Letters Patent is:

1. In combination with a mining machine having a rotatable cutter carrying head, fast and slow speed transmission mechanism and truck driving mechanism, of controlling means including a clutch controlling rotation of said head, clutches controlling said transmission mechanism, a clutch controlling said truck driving mechanism, and operating means for said head rotation control clutch and said truck drive control clutch including a single manually operable controlling member common to the control of both clutches.
2. In a mining machine, a motor, a cable reel, and driving connections between said motor and reel including a drive shaft, a driven shaft, a ratchet mechanism connecting said shafts, and means for releasing said ratchet mechanism to permit relative rotation between said shafts.

3. In a mining machine, a motor, a cable reel, and driving connections between said motor and reel including a drive shaft rotatable in opposite directions, a driven shaft, and a ratchet mechanism connecting said shafts whereby said driven shaft may be rotated in only one direction irrespective of the direction of rotation of said drive shaft.

4. In a mining machine, a motor, a cable reel, and driving connections between said motor and reel including a drive shaft rotatable in opposite directions, a driven shaft, a friction clutch between said shafts, and a ratchet mechanism between said clutch and

driven shaft whereby the latter may be driven in only one direction irrespective of the direction of rotation of said drive shaft.

5. In a mining machine, a motor, a cable reel, and driving connections between said motor and reel including a drive shaft rotatable in opposite directions, a driven shaft, a friction clutch between said shafts, a ratchet mechanism between said clutch and driven shaft whereby the latter may be driven in only one direction irrespective of the direction of rotation of said drive shaft, and means for releasing said ratchet mechanism at will to permit relative rotation between said shafts.

6. In a mining machine, the combination with a rotatable cutter carrying head and rotation mechanism therefor, truck driving mechanism and a plural speed transmission mechanism including fast and slow speed clutches, of mechanism for alternatively applying said clutches and connecting said cutter head rotation mechanism and said truck driving mechanism to said transmission mechanism including a common manual operating element selectively operable to perform the functions stated.

7. In a mining machine, the combination with a rotatable cutter carrying head and rotation mechanism therefor, truck driving mechanism and a plural speed transmission mechanism including fast and slow speed clutches, of mechanism for alternatively applying said clutches and connecting said cutter head rotation mechanism and said truck driving mechanism to said transmission mechanism including parallel shafts, and means for moving one of said shafts axially and rotating the other including a common manual operating element movable to effect either function.

8. The combination with a mining machine having a cutter adjusting and propelling mechanism, of controlling mechanism therefor including a plurality of clutches, and mechanism for alternatively operating said clutches including a cam and lever device, said device including a rectilinearly movable cam and cooperating levers, movement of said cam in one direction effecting swinging of one lever to apply one clutch and movement of said cam in the opposite direction effecting swinging of another lever to apply another clutch.

9. The combination with a mining machine having cutter adjusting and propelling mechanism, of controlling mechanism therefor including a plurality of clutches, and mechanism for alternatively operating said clutches including a cam and lever device, said device comprising a rectilinearly reciprocable shaper member having oppositely inclined cam slots, and an operating lever for each clutch cooperating with each of said slots.

10. The combination with a mining ma-

chine having cutter adjusting and propelling mechanism, of controlling mechanism therefor including a plurality of clutches, and operating means therefor including parallel rods and a common manually operable controlling member for alternatively actuating said rods to effect application of different clutches.

11. The combination with a mining machine having cutter adjusting and propelling mechanism, of controlling mechanism therefor including a plurality of clutches, and operating means therefor including parallel rods and a common manually operable controlling member for actuating said rods alternatively to effect application of different clutches, said controlling member being adapted to move one of said rods axially to operate one clutch.

12. The combination with a mining machine having cutter adjusting and propelling mechanism, of controlling mechanism therefor including a plurality of clutches, operating means for one of said clutches including a rotatable rod, and operating means for another clutch including an operating member reciprocably mounted on said rod and movable longitudinally thereof to effect such clutch control.

13. The combination with a mining machine having cutter adjusting and propelling mechanism, of controlling mechanism therefor including a plurality of clutches, operating means for certain of said clutches including a rotatable rod and an axially movable rod, and operating means for another of said clutches including an operating member reciprocably mounted on said rods.

14. The combination with a mining machine having cutter adjusting and propelling mechanism, of controlling mechanism therefor including a plurality of clutches, and mechanism for alternatively operating said clutches including a rectilinearly reciprocable shipper member having oppositely inclined cam slots, and controlling levers cooperating respectively with said slots.

15. The combination with a mining machine having cutter adjusting and propelling mechanism, of controlling mechanism therefor including a plurality of clutches, a pivoted shipper lever and mechanism for swinging said lever including an axially movable shaft, and means for actuating said shaft including a screw and cooperating nut arranged coaxially therewith and relatively rotatable to effect axial movement of said shaft.

16. The combination with a mining machine having cutter adjusting and propelling mechanism, of controlling mechanism therefor including a plurality of clutches, a pivoted shipper lever and mechanism for swinging said lever including an axially movable shaft and means for actuating said shaft including a screw and cooperating nut arranged

coaxially therewith and relatively rotatable to effect axial movement of said shaft, a manually controllable operating member, and a releasable clutch connection between said screw and operating member.

70

17. The combination with a mining machine having cutter adjusting and propelling mechanism, of controlling mechanism therefor including a plurality of clutches, and operating means therefor including concentric relatively rotatable rods, and a cam and lever device for alternatively rotating said rods, said device including a lever fixed to each rod and cooperating with said cam.

75

18. The combination with a mining machine having cutter adjusting and propelling mechanism, of controlling mechanism therefor including a plurality of clutches, and operating mechanism therefor including coaxially relatively rotatable shafts, a lever fixed to each of said shafts, and a shipper member having inclined cam slots with which said levers respectively cooperate for alternatively swinging the latter.

80

19. The combination with a mining machine having cutter adjusting and propelling mechanism, of controlling mechanism therefor including a plurality of clutches, and operating mechanism therefor including a reciprocable shaft and a rotatable shaft, and a common manually controllable element for actuating said shafts alternatively to effect operation of different clutches.

95

20. The combination with a mining machine having cutter adjusting and propelling mechanism, of controlling mechanism therefor including a plurality of clutches, and operating mechanism therefor including parallel shafts, a toggle mechanism connecting said shafts, a screw for moving one of said shafts axially, and a common manually controllable member for actuating said screw to actuate one shaft and for rotating said other shaft through said toggle mechanism.

100

21. The combination with a mining machine having cutter adjusting and propelling mechanism, of controlling mechanism therefor including a plurality of clutches certain of which are speed controlling clutches, and operating means therefor including a plurality of interconnected shafts, and means for effecting axial movement of one shaft to operate one clutch and for rotating said other shaft to operate another clutch.

105

22. The combination with a mining machine having cutter adjusting and propelling mechanism, of controlling mechanism therefor including a plurality of clutches, and operating means therefor including a plurality of interconnected shafts, and means for effecting axial movement of one shaft to operate one clutch and for rotating said other shaft to operate another clutch, said latter means including a common manually operable controlling element.

110

115

120

125

130

23. The combination with a mining machine having cutter plane adjusting mechanism and propelling mechanism for the machine, of controlling mechanism therefor including a plurality of clutches certain of which are speed controlling clutches while others control said cutter plane adjusting mechanism and still others control both said propelling mechanism and said adjusting mechanism, and operating means therefor including a shaft, and means for rotating said shaft to operate one clutch and for reciprocating said shaft to effect operation of another clutch.

10 24. The combination with a mining machine having cutter adjusting and propelling mechanism, of controlling mechanism therefor including a plurality of clutches, mechanism for alternatively operating said clutches including a reciprocable shipper member having oppositely inclined cam slots and horizontal slots communicating with said inclined slots, levers cooperating with said slots, one lever being adapted to control one clutch, and means for reciprocating said shipper member in one direction for swinging one lever and in the other direction to swing said other lever.

20 25. The combination with a mining machine having cutter adjusting and propelling mechanism, of controlling mechanism therefor including a plurality of clutches, operating means for certain of said clutches including a rotatable rod and an axially movable rod, and a common manual operating element for selectively actuating said rods to effect rotation of the first or axial movement of the second.

30 26. In a mining machine, the combination with machine feeding mechanism including a plurality of controlling clutches one of said clutches having a pivoted operating element while the operating element for another is axially movable, of means including a common controlling element for selectively actuating said operating elements, said controlling element being alternatively connectible to said operating elements.

40 27. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control ele-

45 55 60 65 70 75 80 85 90 95 100 105 110 115 120 125 130

ment for controlling said fast and slow speed clutches and for also controlling at least one of said other clutches.

28. In a mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and also said reversing clutches.

29. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, controlling mechanism for said several clutches including a common control element for controlling said fast and slow speed clutches and for also controlling at least one of said other clutches, and a second common control element operable to control certain of said other clutches.

30. In a mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, controlling mechanism for said several clutches including a common control element for controlling said fast and slow speed clutches and also said reversing clutches, and a second common control element operable to control certain of said other clutches.

ment operable to control the remainder of said clutches.

31. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device.

32. In a mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and also said reversing clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device.

33. A mining machine having truck mounted kerf cutting mechanism disposable

in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts arranged in adjacent parallel relationship respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device.

34. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device, said operating member being operable in one position to move one of said shafts axially to operate the clutch operating device connected therewith.

35. A mining machine having truck

- mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device, said operating member being operable in one position to effect rotation of one of said shafts to operate the clutch operating device connected therewith.
36. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device, said operating member being operable in one position to effect rotation of one of said shafts to operate the clutch operating device connected therewith.
37. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device, said operating member being operable in one position to effect rotation of one of said shafts to operate the clutch operating device connected therewith.
38. In a mining machine, the combination with machine feeding mechanism including a speed controlling clutch and a main feed controlling clutch, of controlling means for selectively actuating said clutches including a common manual controlling element operable to control either of said clutches and movable into different operating positions to effect application of different clutches and rotatable to effect control of either clutch, and means for positioning said controlling element during its transition from one operating position to the other.
39. In a mining machine, the combination with machine feeding mechanism including a plurality of speed controlling clutches and a main feed controlling clutch, of controlling means for said clutches including a common manual controlling element movable into different operating positions to effect control of different clutches and rotatable to ef-

position thereof to move one of said shafts axially to operate the clutch operating device connected therewith and into another position to effect rotation of one of said shafts to operate the clutch operating device connected therewith.

37. A mining machine having truck mounted kerf cutting mechanism disposable in and operative to cut a kerf in each of a plurality of different planes, mechanism for positioning said cutting mechanism, truck driving mechanism for effecting transport and cutting feed of said mining machine, transmission mechanism through which said truck driving mechanism and mechanism for positioning said cutting mechanism are operable including fast and slow speed clutches and reversing clutches, clutches selectively operable to effect transmission of power to said positioning mechanism or to said truck driving mechanism through said other clutches, and controlling mechanism for said several clutches including a common control element for controlling said fast and slow speed clutches and for also controlling at least one of said other clutches, said controlling mechanism including a plurality of shafts respectively connected with the operating devices of the fast and slow speed clutches and said other clutch, and the common control element comprising a manually operable member which is selectively movable relatively to said shafts into different operating positions in each of which it is operable to impart to one of said shafts an actuating movement to operate the respective clutch operating device, said operating member being operable in one position to effect rotation of one of said shafts to operate the clutch operating device connected therewith.

38. In a mining machine, the combination with machine feeding mechanism including a speed controlling clutch and a main feed controlling clutch, of controlling means for selectively actuating said clutches including a common manual controlling element operable to control either of said clutches and movable into different operating positions to effect application of different clutches and rotatable to effect control of either clutch, and means for positioning said controlling element during its transition from one operating position to the other.

39. In a mining machine, the combination with machine feeding mechanism including a plurality of speed controlling clutches and a main feed controlling clutch, of controlling means for said clutches including a common manual controlling element movable into different operating positions to effect control of different clutches and rotatable to ef-

fect application of any of said several clutches, and means for positioning said controlling element during its transition from one operating position to another.

40. In a mining machine, the combination with machine feeding mechanism including a plurality of clutches, one of which is a main feed controlling clutch, of controlling means for said clutches including a common manner controlling element movable bodily into different operating positions to effect control of different clutches and rotatable to effect application of any clutch, and means for positioning said controlling element during its bodily movement from one operating position to another.

41. In a mining machine, the combination with machine feeding mechanism including a plurality of clutches including a main feed controlling clutch, of controlling means for selectively actuating said clutches including a common manual controlling element movable bodily into different operative positions to effect control of different clutches and rotatable to effect application of any clutch, and means for positioning said controlling element during its bodily movement from one operating position to another.

42. In a mining machine, the combination with machine feeding mechanism including a plurality of controlling clutches including a speed controlling clutch and a main feed controlling clutch, one clutch having a pivoted applying element while another clutch has an axially movable applying element, of controlling means for selectively swinging and axially moving said clutch applying elements to effect application of the clutches controlled thereby including a common manual controlling element movable into different operating positions to effect control of different clutches, said controlling element being disconnected from said applying elements during shifting thereof from one operating position to another, and means for guiding said controlling element during its transition from one operating position to another.

43. In a mining machine, the combination with machine feeding mechanism including a plurality of controlling clutches one of which is a main feed controlling clutch, of controlling means for selectively actuating said clutches including a handle common to the actuation of all of said clutches and slideable bodily into one operating position to control one clutch and into a different operating position to control a different clutch, said handle when connected to one clutch being inoperative to effect actuation of another clutch.

44. In a mining machine, the combination with machine feeding mechanism including a plurality of speed and main feed controlling clutches, of controlling means for selectively actuating said clutches including a recipro-

cable handle common to the actuation of all of said clutches and shiftable into one operating position to effect control of one clutch and into a different operating position to effect control of a different clutch, and means for positioning said handle during bodily shifting thereof from one operating position to another.

45. In a mining machine, the combination with machine feeding mechanism including a plurality of speed and main feed controlling clutches, one of said clutches having a pivoted operating element while the operating element for another clutch is axially movable, of means including a common manual controlling element movable into different operating positions and alternatively connectible to said operating elements for selectively swinging and axially moving said operating elements to effect application of different clutches, said controlling element being disconnected from said operating elements during shifting thereof from one operating position to another, and means for guiding said controlling element during its movement from one operating position to another.

46. In a mining machine, the combination with machine feeding mechanism having a plurality of controlling clutches one of which is a main feed controlling clutch, of controlling means for selectively actuating said clutches including a single handle common to the actuation of all of said clutches, said handle being movable into one operating position to effect application of one clutch and into a different operating position to effect application of a different clutch, said handle being disconnected from one clutch when connected in operative relation with another, and means for guiding said handle during its bodily movement from one operating position to another.

47. In a mining machine, the combination with machine feeding mechanism comprising a plurality of speed controlling clutches and a main feed controlling clutch, of controlling means for said clutches including a single handle common to the actuation of all of said clutches, said handle being movable into one operating position to effect application of said main feed controlling clutch and into a different operating position to effect application of either of said speed controlling clutches, said handle being entirely disconnected from the operating means for one clutch when connected to the operating means for another clutch, and means for guiding said handle during its bodily movement from one operating position to another.

48. In a mining machine, the combination with machine feeding mechanism including a speed controlling clutch and a main feed controlling clutch, of controlling means for selectively actuating said clutches including

a rotatable operating rod operatively connected to one clutch and axially movable to effect control of the latter, an operating element for rotating said rod, and means operated upon rotation of said element for effecting application of the other clutch, and means for connecting said operating element to and disconnecting the same from said rod at will.

49. In a mining machine, the combination with machine feeding means including a plurality of selectively operable speed controlling clutches and a main feed controlling clutch, of controlling means for said speed controlling clutches including a single handle for both clutches movable to different operating positions in which it constitutes respectively a speed control clutch control member and a main feed controlling clutch control member, means operated by said handle for operating said main feed controlling clutch, said latter means being disconnected from said handle when the latter is operative to effect application of said speed controlling clutches, and means for positioning said handle during its transition from one operating position to another.

50. In a mining machine, the combination with machine feeding means including a plurality of selectively operable speed controlling clutches and a main feed controlling clutch, of operating means for said speed controlling clutches, operating means for said main feed controlling clutch, a single handle movable bodily into different operating positions for selectively actuating said clutches and alternatively connectible to said clutch operating means, said handle being disconnected from said clutch operating means during bodily shifting thereof from one operating position to another, and means for positioning said handle during its transition between said different operating positions.

In testimony whereof I affix my signature.

CERTIFICATE OF CORRECTION.

Patent No. 1,849,297.

March 15, 1932.

MORRIS P. HOLMES.

It is hereby certified that error appears in the printed specification of the above numbered patent requiring correction as follows: Page 5, line 55, for "arms" read arm; page 6, line 76, strike out the number and words "267 has housed therein a ratchet" and insert instead 23. These contact members 261 slid-; page 13, line 9, claim 40, for "manner" read manual; and that the said Letters Patent should be read with these corrections therein that the same may conform to the record of the case in the Patent Office.

Signed and sealed this 12th day of July, A. D. 1932.

(Seal)

**M. J. Moore,
Acting Commissioner of Patents.**
